UNITED STATES PATENT OFFICE.

EARL L. GLAZE, OF CHILESBURG, KENTUCKY.

MOTOR-TRUCK TURNTABLE.

Application filed May 14, 1925. Serial No. 30,328.

To all whom it may concern:

Be it known that I, EARL L. GLAZE, a citizen of the United States, residing at Chilesburg, in the county of Fayette and State of Kentucky, have invented certain new and useful Improvements in Motor-Truck Turntables; and I do hereby declare the following to be a full, clear, and exact description of the invention, such as will enable others skilled in the art to which it appertains to make and use the same.

The invention relates to turn tables and is particularly designed in turning large motor trucks and has for its principal object the provision of a turn table that is portable in nature so that it may be transported to any place where it is desired to turn motor trucks such for instance as where buildings are being erected, or roads made or repaired, the purpose being to obviate the necessity of turning the truck in the roadway thus blocking traffic, and providing a turn table that is reasonable in cost of manufacture, effective in operation, and that may be readily knocked down for transportation and setting up in the location needed.

The construction and operation and advantages of the invention will be described in detail hereinafter and will be found illustrated in the accompanying drawings, in which—

Figure 1 is a top plan view of the improved turn table,

Figure 2 a side view,

Figure 3 a cross section on a plane indicated by the line 3—3 of Figure 1,

Figure 4 a similar view on a plane indicated by the line 4—4 of Figure 1.

Figure 5 a sectional detail on the line 5—5 of Figure 1,

Figure 6, a sectional detail on a plane indicated by the line 6—6 of Figure 5,

Figure 7, a detail sectional view on the line 7—7 of Figure 1,

Figure 8, a detail view partly broken away and in section showing means for applying rollers to the frame for transportation, and

Figure 9, a sectional view on the line 9—9 of Figure 8.

In the drawings, similar reference characters are used to designate corresponding parts throughout the several views.

The improved turn table is mounted on a base frame comprising a square frame having its four sides, designated 1, made prefer-

ably of channel steel and connected at its corners by angle members 2 secured to the sides 1 by means of bolts 3 that permit dismemberment of said members 1 and 2 when it is desired to move the turn table. 4 indicate braces for the corners of the square frame and secured to the sides 1 by means of bolts 5, said angle braces 4 also formed of channel steel. A circular track is mounted inside of the square frame and comprises two semi-circular members 6 also made of channel steel and having the flanges of the beam extending toward the center of the circle formed by said members 6, said members 6 being secured to the frame by means of bolts 7 engaging said members 6 and the beams 1 and braces 4. The width of the beams forming the members 6 is preferably greater than the width of the beams 1 and braces 4, the preferred proportions being a ten inch channel beam for the members 6, and eight inch channel beams for the members 1 and 4, thus making the members 6 extend two inches above the members 1 and 4 and permitting the beams 1 to act as rests for the upper ends of skids 8 forming inclined approaches to the turn table on the road level.

The turning part of the turn table includes two tracks designated 9 that are preferably made of channel beams and having a flange along each of its longitudinal edges, said flanges being designated 9a. The tracks 9 are connected together by means of arcuate bars 10, preferably made of channel steel, and 11 indicate shorter bars of channel steel secured to the tracks and spaced from the bars 10.

Secured to bars 10 and 11 are journal boxes 12, said journal boxes having ears 13 through which the securing members are engaged. 14 indicates a shaft rotatably mounted in each journal box 12 on which is mounted a roller 15 that traverses the flanges of the circular track made up of the channel beams 6 hereinbefore described. 16 and 17 designate bars connecting arcuate bars 10 and the tracks 9 respectively, and cross intermediate the track and over the center of the circular track formed by the members 6. 18 designate truss beams secured under the beams 1 at the middle of each beam and having their intermediate portions inclined upwardly from the circular track to the middle thereof and form-

ing a support for the crossed beams 16, 17, and 18, and 19 indicates a pivot bolt engaging the beams 16, 17, and 18.

To accommodate trucks of different lengths, the rails 9 are extended at one of their ends at a distance beyond the supporting frame, and the extreme ends of the extended portions are connected by a beam 19^a and an upright sill 20 to form a stop to limit the movement of the truck on the rails. 21 designates a post at the outer end of each rail 9, and 22 a brace therefor, while 23 is a handle member supported by said post on each side and the outer flange of each rail 9, said handles 23 being designed to be used in turning the table.

It will be readily understood that because of the fact that the different parts of the improved turn table are secured together by bolts that can be readily removed that the device is capable of portability and to be set up wherever desired for the purpose intended, and it will be clearly apparent that in operation a minimum amount of space is required to turn the truck and that the turning may be accomplished quickly, thus preventing interference with the ordinary road traffic that would otherwise be interfered with in turning the truck where it is required to do so.

In order that the turn table may be moved short distances without necessitating knocking it down provision is made to mount it on temporary rollers or casters as shown in Figures 8 and 9 in which 24 indicates the wheel or roller journaled between arms 25

on plate 26, 27 being lugs or pins on said plate 26 that engage in openings 28 in the bottom flange of channel beams 1, it being understood that provision must be made for 40 the rollers or casters at each corner of the frame.

What is claimed is:—

1. A turn table comprising a rectangular frame, a circular track comprising semi-circular segments secured together and secured within the rectangular frame, said circular track being of channel construction and having the flanges extending inwardly of the circle, supporting members for the object to be turned comprising flanged rails, arcuate spacing members connecting said rails, and wheels carried by said spacing members and traversing the flanges on the circular track. 55

2. A turn table comprising a rectangular frame, a circular track enclosed by said frame, supporting members for the object to be turned comprising flanged rails, arcuate spacing members connecting said rails, a bar connecting said arcuate members, another bar connecting the rails and at right angles to the first mentioned bar, trussed bars connecting opposite sides of said rectangular frame and crossed intermediate of 60 their ends, a pivot connecting the crossed portions of said bars, and wheels carried by said arcuate members and traversing said circular track. 65

In testimony whereof I affix my signature. 70

EARL L. GLAZE.
